UNITED STATES PATENT OFFICE

170,161

ELECTRIC PERCOLATOR

Robert C. Nicolay, Wooster, Ohio

Application October 25, 1952, Serial No. 21,979

Term of patent 14 years

(Cl. D44—26)

To all whom it may concern:

Be it known that I, Robert C. Nicolay, a citizen of the United States and a resident of the city of Wooster, State of Ohio, have invented a new, original, and ornamental Design for an Electric Percolator, of which the following is a specification, reference being had to the accompanying drawing, forming a part thereof.

Fig. 1 is a side view of an electric percolator, showing my new design;

Fig. 2 is a top view;

Fig. 3 is a rear view showing the handle in elevation; and

Fig. 4 is a front view showing the spout in elevation.

I claim:

The ornamental design for an electric percolator, substantially as shown.

ROBERT C. NICOLAY.
